J. HOELLRIGL

COMBINATION VANITY CASE AND POWDER PUFF

Filed Oct. 28, 1927

Joseph Hoellrigl,
INVENTOR

P. B. Hickey.

WITNESS:

BY Victor J. Evans

ATTORNEY

UNITED STATES PATENT OFFICE.

JOSEPH HOELLRIGL, OF MANCHESTER, NEW HAMPSHIRE.

COMBINATION VANITY CASE AND POWDER PUFF.

Application filed October 28, 1927. Serial No. 229,379.

This invention relates to a novel form of combination vanity case and powder puff wherein such articles as powder perfume, rouge puff, mirror, rouge, vanishing cream, 5 cold cream, lip sticks, eye brow pencils and talcum powder are included whereby the whole set of cosmetics used are very compactly contained and accessible within the compartments.

10 Another object of the invention comprehends a fountain puff adapted to discharge powder therefrom when the puff is called into use.

A further object of the invention embodies 15 a compartment adapted to permit certain of the articles needed to complete a toilet to be readily and easily removed from the compartment without removing the rest of the articles therein, and refilled or replaced when 20 desired.

With the above and other objects in view, the invention further consists of the following novel features and details of construction, to be hereinafter more fully described, 25 illustrated in the accompanying drawing and pointed out in the appended claims.

In the drawings:

Figure 1 is an elevation of the invention.

Figure 2 is a longitudinal sectional view 30 taken on line 2—2 of Figure 1.

Figure 3 is a sectional view taken on line 3—3 of Figure 2.

Figure 4 is a perspective of a powder puff.

Figure 5 is a perspective of a holder member for compact powder.

Figure 6 is a similar view of a holder for vanishing and cold creams.

Figure 7 is a perspective of a partition member adapted to separate the holders from 40 the loose powder compartment and to support lip sticks and eye brown pencils thereon.

Referring to the drawing in detail, wherein like characters of reference denote corresponding parts, the reference character 10 indicates a compartment or casing which is 45 adapted to provide a housing or compartment for the various articles aforementioned. A closure member 11 is hingedly mounted, as indicated at 12, to one side of the casing and 50 adapted for detachable connection upon a diametrically opposite side thereof. The lower face of the closure member 11 lies flush with a mirror 11' which is held thereon through the medium of an annular flange 11². 55 A curved wall 13 is adapted to provide the bottom for the casing and which is in ad-

dition provided with discharge openings 14, the purpose of which will be readily apparent. An annular bead 15 is provided adjacent the connection of the bottom 13 with the casing 10. A false bottom 16 carried beneath the bottom 13 has an upstanding inwardly directed flange portion adapted to be extended over the head 15 and mounted for partial rotation thereon to selectively register openings 18 therein with the discharge openings 14 of the bottom 13; the false bottom 16 and the casing 10 are provided with indicia adapted for registration to coincide to determine registration of the 65 openings therein. The letters C and O indicate the two positions.

A puff 19 preferably sheep wool has the hide 20 lying flush against the underside of the false bottom 16. The marginal edges 75 of the hide 20 are retained against a depending annular flange 21 carried by the false bottom 16 by an expansion ring 22. The die for the puff is provided with openings 80 registering with the openings 18 in the false bottom 16 to facilitate the application of loose powder reposing upon the upper side of the bottom 13 and which is discharged through the puff when the latter is called into use. A partition wall 23 carried within 85 the casing 10 and reposing upon an annular seat 24 therein is provided with depressed pockets 25 adapted to carry a lip stick 26 and eye brow pencil 27. A container 28 having an upstanding annular wall 29 and a partition member 30 is adapted to support 90 vanishing cream and cold cream. A vertically disposed sleeve member 31 carried by and extended centrally of the container 28 is adapted to receive a stud member 32 therein projected from the upper side of the partition 23.

Another container 33 constructed after the manner of the container 28 is in addition provided with a complementary partition 34 dividing the surface of the container into more compartments to accommodate the several varieties of powder compact.

An enlarged sleeve portion 35 carried centrally of the container 33 is adapted to receive the sleeve 31 therethrough in the manner as best illustrated in Figure 2 of the drawing. A head 36 carried upon the upper side of the pin 32 for the partition member 23 may be grasped to withdraw all of the compartments from the container to permit access to the loose powder compartment below the par-

tion 23; the sleeve 31 may be used as a handle to remove containers 28 and 33 together and the sleeve 35 may be grasped to remove the container 33 by itself, leaving the others 5 in the box. A powder puff 37 is positioned upon the upper side of the container 33.

- A tubular handle member 38 carried upon the upper side of the closure or lid 11 is adapted to contain a perfume of a desired fragrance. A cap member 39 for the handle member 38 is provided with a central bore 40 having connection with transverse bores 41 extended within the bore of the handle member to facilitate the shaking of a desired quantity of the perfume through the cap when the latter is partially retracted. The lower cone-shaped portion of the cap provides a tight fitting closure of the bore for the handle member when the cap is tightened.
- From the foregoing description and accompanying drawing, it is apparent that I have provided a simply constructed and inexpensive novelty adapted to carry a number of different toilet articles used every day, the articles being concealed in a powder puff of beautiful design and which obviates the employment of a separate powder box.

The invention is susceptible of various changes in its form, proportions and minor details of construction, and the right is herein reserved to make such changes as properly fall within the scope of the appended claims.

Having described the invention, what is claimed is:

1. A combined vanity case and powder puff comprising a cylindrical casing, a closure lid therefor, a handle member carried by the closure lid, a mirror positioned within the closure lid, a bottom for the casing being convexed and apertured, a false bottom slidably mounted upon the bottom and having openings therein registering with the apertures in the bottom, a puff carried by the false bottom, a partition member carried within the casing adapted to provide a compartment immediately above the bottom for loose powder which may be discharged when the puff is called into use, and containers for different

toilet articles being supported upon the partition.

2. A combined vanity case and powder puff comprising a cylindrical casing, a closure lid therefor, a mirror positioned within the closure lid, a bottom for the casing being convexed and apertured, said bottom adapted to support a quantity of loose powder thereon and to discharge the same through openings therein, a false bottom slidably mounted upon the concaved bottom and having openings therein registering with the openings in the bottom, indicia on the false bottom and on the casing whereby the registering of the openings may be determined, a puff carried by the false bottom from which the powder is applied, a partition member carried within the casing to close the loose powder compartment and which is provided with pockets adapted to carry lip sticks and eye brow pencils, a multiplicity of containers mounted in superimposed relation upon the partition and adapted to carry cosmetics therein, and a handle member for the closure lid.

3. A combined vanity case and powder puff comprising a casing having a convexed bottom wall provided with discharge openings 75 therein, a false bottom slidably mounted upon the bottom and having openings therein adapted for selective registration with the discharge openings in the bottom, a powder puff carried by the false bottom, a partition 80 member carried within the casing adapted to provide a loose powder compartment immediately above the convexed wall, a pin upstanding from the partition member, a multiplicity of containers subdivided to effectively carry a number of cosmetics and provided with centrally disposed sleeve members telescopically associated and adapted to receive the upstanding pin therethrough, said sleeve members and pin serving as handles whereby certain articles may be readily and easily removed from the compartment without removing the rest of the articles therein.

In testimony whereof I affix my signature.

JOSEPH HOELLRIGL.
